UNITED STATES PATENT OFFICE.

JOHN MARKEL, OF MONTICELLO, ILLINOIS.

IMPROVEMENT IN CULTIVATORS.

Specification forming part of Letters Patent No. 31,725, dated March 19, 1861.

To all whom it may concern:

Be it known that I, JOHN MARKEL, of Monticello, in the county of Piatt and State of Illinois, have invented certain new and useful Improvements in Cultivators; and I do hereby declare that the following is a full, clear, and exact description of the same, reference being had to the annexed drawing, making part of this specification, and being a perspective view of a cultivator embodying my improvement.

My invention consists in a combination of hinged cultivator-frames, connecting-link, adjusting-rod, springs, &c., for the purpose of setting the shares to any desired width, and at the same time admitting of their being temporarily adjusted by hand.

The invention further consists in an arrangement of reversible dished wheels for varying the width of tread.

A is the frame of the implement, of rectangular form, as shown, and mounted by means of pairs of downwardly-projecting brackets B B' on wheels C C'. The wheels are considerably dished, and their attachment to the brackets is of such construction as to admit of their being reversed in the bearings when necessary, and thus alter the width of tread to suit the working width of the cultivator-shovels, the latter being also adjustable.

D D' E E' F F' represent, respectively, the beam-handles and shovels of a pair of cultivators, the whole being loosely shackled to frame A at *a* and hinged at *b* to an adjustable connecting-bar, G. A rod, H, passes loosely clear through the handles, and is provided with ad-

justing-nuts *h*, the inside nuts being adjusted against the faces of flat steel springs I, attached to the cultivator-handles. The handles being capable of vibration on the hinges *b*, a longitudinal adjustment of the nuts *h* on rod H acts to increase or decrease the working width of the shovels, the same being also capable of temporary adjustment at any time to clear stones or other obstacles by hand-pressure on the outside of the handles against the springs I. The connecting-rod G is adjustable in length, as stated, to further increase the facility for adjusting the working width of the cultivator-shares, being provided with a series of hinge-perforations, *g*.

The shovels and frames may at any time be raised from the work by means of the treadle, strap, and pulley device J K L, operated by the foot of the driver from seat M.

I claim herein as new and desire to secure by Letters Patent—

1. The combination of devices G b H h I for permanently or temporarily adjusting the working width of the cultivator-shovels, constructed, operated, and operating in the manner substantially as set forth.

2. In combination with the above, the reversible dished wheels C, as fully described, for the purpose set forth.

In testimony of which invention I hereunto set my hand.

JOHN MARKEL.
